UNITED STATES PATENT OFFICE.

LORENZO P. HAWKINS, OF DEERING, ASSIGNOR TO THE GOODYEAR SHOE MACHINERY COMPANY, OF PORTLAND, MAINE.

SOLE-SLITTING MACHINE.

SPECIFICATION forming part of Letters Patent No. 514,364, dated February 6, 1894.

Application filed May 6, 1893. Serial No. 473,193. (No model.)

To all whom it may concern:

Be it known that I, LORENZO P. HAWKINS, of Deering, county of Cumberland, State of Maine, have invented an Improvement in Inner-Sole-Slitting Machines, of which the following description, in connection with the accompanying drawings, is a specification, like letters and figures on the drawings representing like parts.

- 10 In the manufacture of boots and shoes it is found desirable to slit the inner soles transversely in those portions where the shoe is bent in walking. To perform this operation expeditiously and economically, I have devised the machine to be herein described, it having cutters so arranged as to cut two or more rows of slits, the ends of the slits in one row preferably overlapping the ends of the slits in another row.
- 20 Figure 1, in front elevation, represents a machine containing my present invention. Fig. 2, a top or plan view of the sole support and the stripper plates; Fig. 3, a view looking upwardly from the line $x-x$, said view being chiefly to show the cutters, the carriages to which they are attached, and their adjusting devices, and Fig. 4 shows a portion of a sole as it may be slit with my improved machine.
- 30 In the drawings, A represents a suitable table, from which rises a block A' having suitable ears A² to which is secured by bolts B the ears B' of a suitable bed B² which thus becomes fixed to the table. This bed has at its upper side a suitable groove or way, preferably dovetailed in cross section, as shown in Fig. 1, which receives a cutting-plate a upon which the sole to be cut is laid, one end of said sole being pushed in against the registering gages a' a'', the cutting plate being free to be slid out and into the groove in the bed so as to put the part of the sole s to be slit, as at 2, 3, in under the cutter blades b. The bed b² has mounted on it, preferably in an adjustable manner by screws c, a stripper C shown as having a series of fingers between which are slots for the passage of the blades b, the screws c entering slots c' in the shanks of the strippers, so that said strippers may be 45 adjusted as required to put them in proper position with relation to the blades b, and the

portions of the sole to be cut. Preferably the shanks of the strippers will be provided at their under sides with a channel or way for the reception of the shank of an edge gage d, 55 the front end of which is shown by dotted lines Fig. 2, said gage when pushed forward or inwardly from its dotted line position, as it may be by releasing set screw 2, serving as a gage for the edge of the sole, the shank of 60 the edge gage having a suitable slot 3. The upright part of the frame-work has at its front end a suitable bearing A^x, in which is fitted to slide a plunger D to which is suitably jointed the rod D' of an eccentric strap D² 65 embracing a proper eccentric D³ on the end of a power actuated shaft D⁴, said shaft, eccentric, link, plunger and bearing being common to power actuated hammers or pressers, so need not be herein further described. The 70 lower end of the plunger has clamped upon it by clamp screw E a block or head E', said head being suitably shaped at its under side to receive like carriages E², E³, entered the one by a right and the other by a left hand 75 screw-thread carried by adjusting screws E⁴, E⁵, each of said screws having an annular groove about it which receives a portion of the head E', so that the said screws, while they are capable of being rotated, cannot 80 move longitudinally, and consequently the carriages E², E³, will be moved in suitable guiding grooves of the head, and by these the knives b, b', attached to said carriages, may be made to approach toward or be separated 85 one from the other, according as it is desired that the cuts or slits made in either shall overlap one the other more or less or be removed from each other so as to make slits alternately in different lines, dodging slits. 90

I have attached to the carriages certain indicating fingers e which co-operate with a scale e' cut or marked on the head E', so that when the adjusting devices are turned, the positions of the acting ends of the cutters may 95 be assured equally distant, or at the desired distance from the center or zero line of the scale.

With a sole placed upon the cutting-plate a under the strippers C, the plunger will be 100 moved to descend, and the blades b will descend through the slots in the strippers and

cut into and through the sole or for the distance desired, the sole so cut being made flexible, so that it will bend with greater ease and adapt itself to the foot in walking.

5 Having described my invention, what I claim as new, and desire to secure by Letters Patent, is—

1. In a machine for slitting leather the following instrumentalities, viz:—a cutting plate, strippers, and two series of blades set one series with relation to the other series to cut two rows of slits, the slits of one row being in line with the spaces between the slits of the other row, and with devices to adjust the separate rows of blades, and the carriages to which they are attached with relation to each other to place the rows of slits made by the blades more or less close together, substantially as described.
- 10 2. In a machine for slitting leather, the following instrumentalities, viz:—a cutting plate, strippers, and two series of blades set one series with relation to the other to cut two rows

of slits, the slits of one row being in line with the spaces between the slits of the other row, and with devices to adjust the said blades one set toward or from the other set, and devices to adjust the strippers, substantially as described.

15 3. In a machine for slitting soles, a cutting plate having gaged projections, and made movable under series of cutters, combined with two stripper-plates, and with two sets of cutters the blades of one set being arranged in line with the spaces between the blades of the other set, carriages to which the said blades are attached, and adjusting devices by which to adjust the said sets of blades, substantially as described.

20 In testimony whereof I have signed my name to this specification in the presence of two subscribing witnesses.

LORENZO P. HAWKINS.
